UNITED STATES PATENT OFFICE.

LANDO LOCKER AND OBBIE M. FRAZIER, OF HOISINGTON, KANSAS.

SOFT-DRINK REFRIGERATOR.

Application filed December 2, 1926. Serial No. 152,203.

This invention relates to soft drink refrigerators and more particularly to a device of this character intended for use in cooling and dispensing bottled soft drinks.

5 An important object of the invention is to provide a device having conduits through which the bottled drinks may be fed and within which they are cooled in passage, the construction of the conduits being such 10 that bottles of different sizes may be inserted in the same conduit, without danger of these bottles wedging or sticking therein.

A more specific object of the invention is the provision of a conduit for use in a 15 refrigerator of this character having a yieldable wall which fits against the body of a bottle without regard to the size thereof.

These and other objects we attain by the 20 construction shown in the accompanying drawings, wherein for the purpose of illustration is shown a preferred embodiment of our invention and wherein:

Figure 1 is a side elevation of a refrigerator constructed in accordance with our invention;

Figure 2 is a transverse sectional view therethrough;

Figure 3 is a fragmentary longitudinal sectional view therethrough;

30 Figure 4 is a fragmentary top plan view thereof;

Figure 5 is a side elevation partially in section of the plunger for removing obstructions or waste from the tubes.

35 Referring now more particularly to the drawings, the numeral 10 indicates an outer casing having arranged therein outer and inner U-shaped troughs 11 and 12, the ends of which are connected to one another by 40 end walls 13, with the result that a central compartment 14 is provided which will hereinafter be referred to as the refrigerant compartment and a U-shaped longitudinally extending conduit is formed between the inner and outer U-shaped troughs 11 and 12. Between the outer trough 11 and outer casing a filling of heat insulating material 15 is placed. The top of the refrigerant compartment is closed, preferably by a cover 16 formed in two sections hinged to one another, as at 17, so that access may be had to the interior of this compartment without completely uncovering the same.

50 The U-shaped conduit between the inner and outer U-shaped troughs is subdivided by a plurality of U-shaped partitions 18 into a

plurality of bottle conduits 19, each of which is provided at each end thereof with a spring hinged cover 20. Each bottle conduit 19 is provided with a false wall 21 60 consisting of a strip of flexible material secured at one end to the outer U-shaped trough at the upper edge thereof and having its opposite end free. Between the wall of the U-shaped trough and this false wall are 65 disposed a plurality of springs 22 constantly urging this false wall toward the opposed wall of the conduit formed by the inner U-shaped trough 12. These springs keep 70 the false wall 21 in constant engagement with the bottles passing through the bottle conduit without regard to the size thereof, so that the neck of a bottle is prevented from passing the base of a bottle in advance thereof. An occurrence of this sort will 75 cause jamming of the bottles in the conduit, with the result that a tedious operation is necessary to restore the operation. The springs 22 are preferably formed of non-corrosive material, for a purpose which will 80 presently appear.

Secured to one end of the outer casing 10 is a control device for regulating the depth of liquid within the lower portions of 85 the conduits 19 and the refrigerant chamber 14. This device includes a sight glass 23, an outlet control pipe 24 and an outlet pipe 25, which may be connected at its lower end to the sewer. The lower ends of the sight glass 23 and outlet control tube 90 24 are connected by a header 26 which is in turn connected with the bottom of the trough 11 by a conduit 27. The partitions 18 and the bottom trough 12 have perforations 28 and 29 respectively, permitting circulation of fluid therethrough. The upper ends of the sight glass 23, outlet control pipe 24 and outlet pipe 25 are connected to one another, as at 30, and the outlet control pipe 24 is further connected with the outlet pipe 100 25 by a plurality of valved conduits 31, 32 and 33 arranged at different levels. By opening a selected conduit 31, 32 or 33 or closing all of these conduits and permitting the water to flow to the outlet through the 105 connection 30, a desired level of fluid may be maintained in the bottle conduits and in the refrigerant compartment.

If desired, a coil 34 may be arranged in 110 the bottom of the refrigerant compartment 14 and provided at the upper end of the refrigerator with a valved outlet, so that

this coil may serve for cooling soft drinks in bulk containers. The walls of the casing 10 preferably are constructed to include the necessary cash drawers 35 and 5 to support a bottle cap remover 36 and a receptacle 37 for the removed caps. It will be obvious that with a device of this character, a bottle will occasionally be broken within a bottle conduit and we accordingly 10 provide a plunger comprising a flexible shaft 38 having at one end a head 39 adapted to pass through the conduit and force before it anything which may be within the conduit and at its opposite end a handle 40, by means of which it may be manipulated. It will be obvious that this plunger may also be employed to clear the conduit of bottles when it is not desired that further bottles be inserted thereto and to remove from 15 the conduit bottle labels which are washed from the bottles during their passage through fluid contained in the conduits. Since the construction hereinbefore set forth is capable of a certain range of change and modification without materially departing from the spirit of the invention, we do not limit ourselves to such specific structure except as hereinafter claimed.

We claim:

30 1. In a bottle refrigerator, a conduit through which the bottles may pass and means for refrigerating said conduit, said

conduit including a flexible false wall and means yieldably urging said flexible false wall toward the opposite wall thereof. 35

2. In a bottle refrigerator, a conduit through which the bottles may pass and means for refrigerating said conduit, said conduit having upon one wall thereof a plurality of springs and a false wall supported 40 from said springs and urged thereby toward the opposite wall of the conduit, said false wall being flexible whereby it engages bottles arranged within the conduit without regard to the size thereof. 45

3. In a bottle refrigerator, an outer casing, inner and outer U-shaped troughs arranged within the casing, a common wall for said troughs, a cover for the inner trough between the end walls whereby said inner trough provides a refrigerant chamber, partitions subdividing the space between the outer and inner troughs into a plurality of transversely extending U-shaped bottle channels, the inner face of the outer trough 50 having attached thereto adjacent one end of each conduit the ends of flexible false walls for the conduits and means yieldably urging said false walls toward the wall of the inner trough. 55

In testimony whereof we hereunto affix our signatures.

LANDO LOCKER.
OBIE M. FRAZIER.
